CUSHION DOORSTOP

George Johnson, Los Angeles, Calif.

Application November 7, 1950, Serial No. 194,509

4 Claims. (Cl. 16—82)

1

This invention relates to the building art, and more particularly to an assembly for silencing the closing of a door and cushioning the shock of the door as it is closed.

The object of the invention is to provide an assembly for minimizing the noises that result when a door is closed, the assembly of the present invention also cushioning the shock of the door as it is closed.

Another object of the invention is to provide a door check assembly which will provide a substantially air-tight joint to eliminate the loss of heat from the building, the assembly of the present invention being easily installed.

Another object of the invention is to provide a door check assembly which is extremely simple and inexpensive to manufacture.

Other objects and advantages will be apparent during the course of the following description.

In the accompanying drawing forming a part of this application, and in which like numerals are used to designate like parts throughout the same:

Figure 1 is a fragmentary front elevational view of a conventional door equipped with the door check of the present invention;

Figure 2 is a sectional view taken on the line 2—2 of Figure 1;

Figure 3 is a sectional view taken on the line 3—3 of Figure 2;

Figure 4 is an elevational view of the cushion strip;

Figure 5 is a fragmentary perspective view of the cushion strip broken away and in section to further illustrate the construction thereof;

Figure 6 is a view similar to Figure 4, but illustrating a modified form of the cushion strip; and

Figure 7 is a view similar to Figure 4, but showing another modified cushion strip.

Referring in detail to Figures 1 through 5 of the drawings, the numeral 10 designates a door frame, Figure 1, and the door frame 10 includes vertical portions 11 and 12, and a horizontal upper section 14. A conventional door 15 is hingedly connected to the vertical portion 11 by hinges 16, and the present invention is directed to an assembly for silencing and cushioning the door 15 when the door is closed.

The door check assembly of the present invention includes a cushion strip 17 and a cushion strip 18, the strip 17 being arranged contiguous to the inner surface of the vertical portion 12, while the strip 18 is arranged contiguous to the lower surface of the horizontal portion 14. Since the strips 18 and 17 have the same construction, only the strip 17 will be described in detail, and this will suffice for both.

The strip 17 has an outer tapered or inclined edge 19, Figures 2 and 5, so that when the door 15 closes, there will be a minimum of surface contact between the door 15 and the beveled or inclined edge 19, so that there will be a minimum amount of noise when the door is closed. The edge opposite to the beveled edge 19 may be provided with a fancy configuration, as 20, and the edge 20 may have any desired shape or design.

The strip 17 is provided with a plurality of pockets or recesses 21 which are arcuate in shape, as best seen in Figures 2 and 5. Seated in each of the recesses 21 is a rubber bumper or cushion 22, and the rubber cushions 22 may be secured in the recesses 21 by any suitable means, as by glue.

The portions of the strip 17 which are in between the cushions 22 are indicated by the numeral 23, Figure 3, and suitable securing elements, such as nails 24, extend through the portions 23 and into the door frame, so as to secure the strip 17 or 18 to the door frame.

It will be seen from Figure 4 of the drawings that the rubber cushion 22 has a rectangular shape on its outer surface, but referring to Figure 6, there is shown a modified strip which is adapted to be used in the same manner as the strip 17. The strip shown in Figure 6 is indicated by the numeral 25, and the strip 25 is provided with a plurality of cylindrical sockets 27, and seated in each of the sockets 27 is a cylindrical cushion or bumper 26 which is fabricated of rubber. In Figure 7 there is shown another modified assembly, wherein the strip is indicated by the numeral 29, and the strip 29 includes a plurality of diamond-shaped cushions or bumpers 28 which are seated in diamond-shaped recesses or sockets 30.

From the foregoing it is apparent that an assembly has been provided which will silence the closing of the door 15 and also cushion the shock of the door as it is closed. The strip 17 or 18 includes the beveled edge 19, so that when the door 15 closes, the contact surface between the strip 17 and the door 15 will be at a minimum, so that there will be no slamming or a minimum of noise. Also, the rubber cushions 22 insure that when the door 15 closes, the strip 17 will be able to move slightly, the cushions 22 acting as a shock absorber, whereby noise and damage to the parts will be minimized. The strips 25 and 29 have substantially the same construction and

function as the previously-described strip 17, except that the strip 25 has cylindrical bumpers 26, while the strip 29 has diamond-shaped bumpers 28.

As previously stated, the beveled edge 19 prevents the door from slapping, and the assembly of the present invention eliminates the necessity for a wooden door stop. Also, the assembly of the present invention is attractive and does not interfere with the normal operation of the door.

I claim:

1. In a door check, a strip adapted to be secured to a door frame, there being a plurality of recesses arranged in said strip, a rubber cushion seated in each of said recesses, one side of said strip being beveled and adapted to be engaged by the door, and securing elements extending through said strip for connecting said strip to said door frame, said cushions engaging the inner surface of the door frame, said securing elements projecting between said cushions into the door frame.

2. In a door check, a strip adapted to be secured to a door frame, there being a plurality of recesses arranged in said strip, a rubber cushion seated in each of said recesses, one side of said strip being beveled and adapted to be engaged by the door, said cushions being cylindrical in shape, and securing elements extending through said strip for connecting said strip to said door frame, said cushions engaging the inner surface of the door frame, said securing elements projecting between said cushions into the door frame.

3. In combination, a door frame, a door hingedly connected to said frame, and a door check, said door check including a strip arranged contiguous to the inner surface of said door frame,

said strip having an inclined outer surface adapted to be engaged by the door, there being a plurality of curved recesses arranged in said strip, a rubber cushion seated in each of said recesses and secured to said strip, and securing elements extending through said strip for connecting said strip to said door frame, said cushions engaging the inner surface of the door frame, said securing elements projecting between said cushions into the door frame.

5. A door check comprising a strip adapted to be arranged contiguous to the inner surface of a door frame, said strip having an inclined outer surface adapted to be engaged by a door, there being a plurality of curved recesses arranged in said strip, a rubber cushion seated in each of said recesses and secured to said strip, and securing elements extending through said strip for connecting said strip to said door frame, said cushions engaging the inner surface of the door frame, said securing elements projecting between said cushions into the door frame.

15 20 GEORGE JOHNSON.
